UNITED STATES PATENT OFFICE.

HENRY C. ZENKE, OF RICHMOND HILL, NEW YORK.

METAL-MOLDING APPARATUS.

Application filed November 14, 1921. Serial No. 514,919.

To all whom it may concern:

Be it known that I, HENRY C. ZENKE, a citizen of the United States, residing in Richmond Hill, county of Queens, State of New York, have invented an Improvement in Metal-Molding Apparatus (Case "B"), of which the following is a specification.

This invention relates to apparatus for molding metals and more particularly to apparatus for casting type lead, such as is used in the printing art, into pigs.

One of the objects of this invention is to provide a simple and practical metal molding apparatus by means of which type metal, for example, may be cast into pigs of convenient size and shape, such for example as may be readily fed to type-casting machines, and in which simplicity of construction is combined with facility of operation when in use.

Another object is to provide a practical and effective means for securing the several parts of the molding apparatus together for receiving the molten metal.

Another object is to provide a metal molding apparatus from which the cast pigs may be readily ejected with a minimum effort and in which the separation of the several parts of the molding apparatus to permit the ejection of the pigs may be effected in a simple manner and with a minimum expenditure of manual effort.

Other objects will be in part obvious or in part pointed out hereinafter.

To embody my invention I have provided a central upright standard with mold members hinged thereto with a clamping device for securing the parts together during the process of molding and means for ejecting the molded pigs of metal when the mold is opened.

In the accompanying drawings in which is shown an embodiment of my invention.

Figure 1 is a perspective view of the molding apparatus showing the several parts in assembled but open position;

Figure 2 is a perspective view showing the several parts of the molding apparatus in closed position and locked together in readiness to receive the molten metal;

Figure 3 is a plan view on an enlarged scale of the clamping device for holding and locking the several parts in closed position; and

Figure 4 is a partial sectional view on the line 4-4 of Fig. 3, showing the details of

the toggle embodied in the locking device of Fig. 3; and

Figure 5 is a partial sectional view on the line 5-5 of Fig. 1 on an enlarged scale 60 showing the details of the pig ejecting mechanism.

Like reference characters refer to like parts throughout the several views in the drawings.

Referring now to the drawings and more particularly to Fig. 1, there is shown a main supporting member 10 provided at its lower end with suitable standards 11 and 12 for maintaining the supporting member 10 in a vertical or upright position. To the upper end and at one side of the supporting member 10 there is secured a bracket 13 provided with two oppositely extending arms 14 and 15, each extending away from the supporting member 10. To the upper end and upon the opposite side of the supporting member 10 there is secured a bracket 16 similarly positioned and of similar construction as the bracket 13 so as to provide 80 two oppositely extending arms 17 and 18. The arms 14 and 17 form a pair of supports for a mold member 19, at the upper end of which there are suitable outwardly extending arms 20 and 21, the outer ends of which are pivotally connected by means of the rod or pin 22 to the outer ends of the supporting arms 14 and 17 respectively. A handle 23, preferably formed integral with the arm 20 of the mold member 19, swings the mold member 19 about its pivotal suspension.

To the outer ends of the other pair of arms 15 and 18 there is suspended another mold member 24 by suitable arms 25 and 26 and by the pin 27, a handle 28 forming an 95 extension of the arm 26 being provided for manually controlling the position of the mold member 24. The mold members 19 and 24 are of substantially identical construction and are suspended with respect to the 100 supporting member 10 in substantially identical manner as already set forth. Hence, only one of the mold members 19 and 24 will be described in greater detail together with its associated operating mechanisms.

As may be clearly seen in Figs. 1 and 2, each mold member is preferably provided with two metal-receiving spaces or compartments, whose dimensions and shape are such as it is desired to give the cast pig. Thus the mold member 19 is provided with two metal-receiving spaces 29 and 30 and the

mold member 24 is shaped to form two spaces 31 and 32 adapted to give the pigs the desired conformation. The wall, such as the wall 33 in the mold member 19, which 5 separates the two metal-receiving chambers is preferably cored out to provide at the exterior of the mold member a series of open recesses as 34, thus to increase the surface exposed to the atmosphere and therefore to 10 increase the radiation of heat from the mold. Excessive masses of metal which tend to retain heat are thus avoided in the construction of the mold-forming parts and a more rapid cooling of the structure is thus attained.

Each face of the supporting member 10 has its surface raised as at 35 in an outline corresponding substantially to the outline 20 of the inner end faces of the wall-forming portions of the mold members 19 and 14. The raised portions 35 of the supporting member 10 may thus be readily machined or finished so that the correspondingly machined or finished edges of the wall-forming 25 portions of the mold members 19 and 24 may snugly contact therewith and form a metal-tight connection therebetween. The supporting member 10 is preferably cored out so that a supply of cooling water may 30 be circulated through its interior, as by means of the pipe connections 36 and 37, which may function as the inlet and outlet respectively.

By reason of the eccentric pivotal suspension of the mold members 19 and 24 to the supporting member 10, as hereinbefore described, each mold member will tend to swing in an outward direction or away from the supporting member 10 and into the position shown in Fig. 1. This action takes 35 place because the axis of suspension of each mold member is positioned exteriorly of the vertical plane passing through the center of gravity of each mold member and exteriorly also of the supporting member 10. In other words, the pivot point of each mold member is positioned eccentrically with respect to the center of gravity of the corresponding mold member. Each mold member 40 19 and 24 may be swung inward and into contact with the supporting member 10 by means of the operating handles 23 and 28 respectively, thus to permit the supporting member 10 to function as the closing side for 45 each metal-receiving space or compartment in each of the mold members 19 and 24. In order, however, to hold temporarily each mold member 19 and 24 in the closed position so as to permit of the application of a 50 suitable clamping device for locking the several parts in closed position, I have provided an automatically operating latch adapted to hold each mold member in closed position. As shown in Fig. 1, there is mounted at 55 preferably the lower part of the end wall of the

member 10 a pin 38 which is adapted to be engaged by the hook portion or latch 39 on the inner end of a lever 40 pivotally mounted at the lower exterior portion of each mold member 19 and 24. The lever 40 is preferably secured to one end of a shaft 41 mounted in the bearings 42 integrally formed in a suitable housing 43, which may be mounted upon the exterior and lower portion of each mold member in any suitable 60 manner.

Each housing 43 is formed into two chambers 44, one for each of the mold-receiving spaces in each mold member. In Fig. 5 of the drawings is shown a vertical sectional view taken through one of the chambers 44 and it will be noted that to the shaft 41 there is secured an arm 45 adapted to be contacted with by the pin 46 sliding in the end wall 47 of the housing 44 and projecting through the outer wall of the mold member 19. A spring 48 surrounds the pin 46 and is interposed between the wall of the mold member 19 and a pin or collar 49 rigidly secured to the pin 46. The spring 48 thus urges the pin 46 outwardly. A second pin or collar 50 mounted at the upper end of the pin 46 and adapted to engage with the inner face of the wall 47 of the housing 44 limits the upper movement of the pin 46 in response to the action of the spring 48 so as to maintain the lower end face of the pin 46 substantially flush with the interior face of the outer wall of the mold member 19.

The spring 48, however, also tends to rotate the shaft 41 in a counter-clockwise direction, as viewed in Fig. 5, and hence tends to maintain in an upper position the outer end of the lever 40 at which the hook portion or latch 39 is mounted. As each mold member 19 and 24 is swung inward into the closed position, as shown in Fig. 2, the latch 39 on each mold member 19 and 24 will engage with the pin 38 and will be held in engaged position by the action of the spring 48. The mold members 19 and 24 are thus held against the action of gravity in the closed position by their respective latches 39.

In order to lock each mold member against the main supporting member 10 which, as hereinbefore noted, thus forms the closing side of the metal-receiving spaces in the mold member, there is provided a clamping device comprising the yoke member 51 secured at its central portion to a middle part of the end wall of the supporting member 10 by means of a hinge 52, more clearly shown in Fig. 3 of the drawings. The yoke 51 may thus be swung from the position shown in Fig. 1, in which it is out of engagement with the several mold-forming parts, into the position shown in Fig. 2 in which the two mold members 19 and 24 with their common interposed supporting member 10 are adapted to be engaged by the several devices mounted 115 120 125 130

in the ends of the yoke 51. One end of the yoke 51 is adapted to engage the mold member 24 at a substantially central point therein by the screw 53 threaded into the boss 54 formed in the one end of the yoke 52 and substantially opposite a boss 55 in the opposite end of the yoke 51. The boss 55 is bored out to provide a substantially cylindrical guide for a plunger 56 which is adapted to be moved toward or away from the screw 54 in the opposite end of the yoke by means of a suitable toggle. This toggle (see Figs. 3 and 4) comprises the link 57 in pivotal engagement with the outer end of the plunger 56 and a complementary toggle-forming member comprising a pair of links 58 pivoted upon the bolt 59 mounted on the boss 60. The link 57 is pivotally connected to the pair of links 58 by a pin 61 which extends through a yoke 62 whose upper end is bifurcated as at 63 to receive the operating handle 64 pinned thereto by means of the pin 65. The operating handle 64 is suitably pivoted at its one end to the yoke 51 as at 66. The two arms of the lever may be given any desired proportion according to the multiplying effect desired to be attained.

The mold members 19 and 24 having been placed in the closed position by means of their respective operating handles 23 and 28 and having been held in such closed position by their respective latches 39, the yoke 51 is thereupon swung into the position shown in Fig. 2 by means of the operating handle 64. Continued movement of the operating handle 64 causes the operation of the toggle 57-58 so as to force the plunger 56 inward. The mold members 19 and 24, in engagement respectively with the plunger 56 and the screw 53, are securely clamped and locked against the supporting member 10 and the several parts are in readiness to receive a charge of molten metal. The degree of tightness with which the several parts are clamped together may be readily adjusted by means of the screw 53 forming one of the contacting parts of the clamping device, and it will be noted that this adjustment may readily be made with respect to the toggle-forming links 57 and 58 so that the toggle is straightened out and locked at the desired adjustment.

Upon the cooling and setting of the metal within the several mold-receiving spaces, the clamping device is unlocked and swung about its hinge 52 and into the position shown in Fig. 1. The mold members 19 and 24, however, will be retained in a closed position by reason of the action of the latches 39 hereinbefore described. At the opposite end of the shaft 41, however, there is mounted an operating lever 67 which is preferably formed for operation by the foot of the operator. This treadle or lever 67, when operated by the operator, causes such a ro-

tation of the shaft 41 as will swing the latches 39 away from their respective pins 38 and permit the action of gravity to become effective to swing the mold members into the position shown in Fig. 1. The same movement of the shaft 31 by virtue of the lever 61 is effective also to cause an inward movement of the pin 46, there being one for each metal-receiving space as hereinbefore described, against the action of the spring 48. The pig cast within each space is thus dislodged from the walls of the mold members 19 and 24 and is readily discharged therefrom and between the parts now in the position shown in Fig. 1. It will be understood that the release of the latches 39 and the ejecting movement of the pins 46 are initiated by the same operation of the lever 67 and, furthermore, that the effort applied to the lever 67 is applied in such direction as to assist the action of gravity in swinging the respective mold members away from the main supporting member to permit the discharge of the cast pigs.

In the embodiment hereinbefore described, each mold member 19 and 24 has been described as having two metal-receiving spaces, but it will be understood that a greater or smaller number of metal-receiving spaces may be incorporated in each mold member. It will be noted in Fig. 2 that irrespective of the number of metal-receiving spaces employed, the upper open ends of the molds are in close proximity to one another so as to facilitate the rapid pouring of metal into the several metal-receiving spaces.

It will thus be seen that there has been provided in this invention apparatus whose construction is of itself substantially simple and which lends itself to relatively inexpensive manufacture. It will further be seen that the operation of the several parts is simple and practical and that a minimum amount of effort need be exerted in the manual operation thereof, thus bringing about convenience in manipulation. Furthermore, it will be noted that in this apparatus the several objects of this invention, as well as many advantages, have been attained.

As many possible embodiments may be made of this invention and as many changes might be made in the embodiment above set forth, it will be understood that all matter herein set forth is to be interpreted as illustrative and not in a limiting sense.

I claim as my invention:

1. In apparatus of the character described, in combination, a mold including two cooperating and separable parts for receiving a molten metal, means pivotally connecting said parts, means tending to swing one of said parts about said pivotal connecting means and away from the other part, and an

- automatically operative latch for locking said parts together.
2. In apparatus of the character described, in combination, a mold including two co-operating and separable parts for receiving a molten metal, means pivotally mounting one of said parts with respect to the other of said parts whereby the action of gravity tends to swing said pivotally mounted part 10 away from said other part, and an automatically operative latch for locking said parts together against the action of gravity.
3. In apparatus of the character described, in combination, a mold including two co-operating and separable parts for receiving a molten metal, means pivotally connecting said parts, means tending to swing one of said parts about said pivotal connecting means and away from the other part, an 20 automatically operating latch for locking said parts together, and means for clamping said two parts together.
4. In apparatus of the character described, in combination, a mold including two co-operating and separable parts for receiving a molten metal, means pivotally mounting one of said parts with respect to the other of said parts whereby the action of gravity tends to swing said pivotally mounted part 30 away from said other part, an automatically operative latch for locking said parts together against the action of gravity, and means including a toggle for locking said parts together.
5. In apparatus of the character described, in combination, a mold including two separable and cooperating parts for receiving a molten metal, means for pivotally connecting one of said parts with respect to the other, means operative to swing said pivotally connected part away from the other, a latch for locking said parts together, manually operative means for unlocking said latch, and means operative upon the operation of said last mentioned means for dislocating the molded metal from said part.
6. In apparatus of the character described, in combination, a mold including two co-operating and separable parts for receiving a molten metal, means pivotally mounting one of said parts with respect to the other whereby the action of gravity tends to swing said part away from the other part 55 thereby to permit the discharge of the molded metal from said parts, means for locking said parts together against the action of gravity, means for dislocating the molded metal from one of said parts, and manually operative means for substantially simultaneously unlocking said locking
- means and for operating said dislocating means.
7. In apparatus of the character described, in combination, a mold including two co-operating and separable parts for receiving a molten metal, means for pivotally connecting one of said parts with respect to the other, means for clamping said parts together, means pivotally mounting said clamping means with respect to said parts whereby said clamping means may be swung into or out of clamping position, and separate means for dislocating the molded metal from one of said parts. 75
8. In apparatus of the character described, in combination, a vertically extending supporting member, a pair of mold members supported from said member, one on each side of said member and adapted to be moved toward or away from said supporting member, said supporting member forming a closing member common to each of said mold members, means for clamping said members together, and means pivotally mounting said clamping means upon said supporting member whereby said clamping means may be swung into or out of clamping position with respect to said mold members. 80
9. In apparatus of the character described, in combination, a vertically extending supporting member adapted to form one part of a mold, a supporting bracket attached to the upper end of said supporting member 85 and extending away from said member, a main mold member adapted to cooperate with said supporting member to form a mold for receiving a molten metal, and means pivotally connecting said mold member to the outer end of said bracket. 90
10. In apparatus of the character described, in combination, a vertically extending supporting member, a pair of supporting brackets mounted at the upper end thereof and extending away therefrom, a main mold member adapted to form with said supporting member a mold for receiving a molten metal, a pair of arms secured to the upper end of said mold member and extending away therefrom, means pivotally connecting said pair of supporting brackets and said pair of arms at the outer ends thereof whereby the action of gravity tends to swing said mold member away from said supporting member, and means for securing said mold member in operative relation to said supporting member. 105
- In testimony whereof, I have signed my name to this specification this fourth day 110 of November, 1921.
- HENRY C. ZENKE.
